Sellers Patent

The Schedule referred to in this Seller's Patent and making part of the same containing a description in the words of the said Benjamin Franklin himself of the "Economical candlestick."

The Economical candlestick consists of a number of tubes or hollow cylinders, sliding one within another, of as many different grades, sizes, as may be thought necessary for the various sizes of the candlesticks, which may be required to be used therein. Each of the upper tubes, being made a little longer than the next lower one, admits of giving a long or a handle or bath on the lower ends of all of them, whereby they may be easily removed. On the center a solid cylinder or tube (the ends of which may be closed) is made fast to the bottom of the candlesticks by a screw or otherwise, round this the others move up and down. The upper tube or solid cylinder may be so long as to rise above the others, when they are drawn down, where by the last pair of the candle may be burnt independent of the sliding tubes and above them, so that the shadow of the iron on the candle wick tube may be greatly reduced at the last union of the wicks. The rest the sliding tubes will then be kept cool to prevent the candle melting immediately without melting it. A spring or springs may be placed in a variety of ways to keep the sliding tubes up, the best mode of making an spring for this purpose may perhaps be by a wire which is fastened to the bottom having its top made to spring against the side of the center tube. The bottom may be round, square or any other regular and solid instrument or any part of it may be made of any metal or combustible substance which may be profound.
